UNITED STATES PATENT OFFICE.

JULES H. VENON, OF NEW YORK, N. Y.

DESIGN FOR A GOBLET OR SIMILAR ARTICLE.

Application filed February 18, 1925. Serial No. 12,413. Term of patent 7 years.

To all whom it may concern:

Be it known that I, JULES H. VENON, a citizen of the United States, and resident of the city, county, and State of New York, have invented a new, original, and ornamental Design for a Goblet or Similar Article, of which the following is a specification, reference being had to the accompanying drawing, forming part thereof.

In the drawing is shown, in elevation, a goblet of fancy ornamental glassware, show-

ing my new design. Fig. 2 is a top view on line 2—2 of Fig. 1.

The important feature of the design is the numerous vertically extending wavy curves and curving surfaces of the bowl of the article.

I claim:—

The ornamental design for a goblet or similar article, as shown and described.

J. H. VENON.
